DESIGN FOR A GAME APPARATUS

Emmett E. Weaver and Roy E. Kamp,
Fort Worth, Tex.

Application July 30, 1936, Serial No. 64,135

Term of patent 3½ years

To all whom it may concern:

Be it known that we, Emmett E. Weaver and Roy E. Kamp, citizens of the United States, residing at Fort Worth, in the county of Tarrant, the State of Texas, have invented a new, original, and ornamental Design for a Game Apparatus, of which the following is a specification, reference being had to the accompanying drawing, forming part thereof.

We claim:

The ornamental design for a game apparatus substantially as shown.

EMMETT E. WEAVER.
ROY E. KAMP.
